CLOTH MEASURING AND TUBING MACHINE

George W. Lane, Clifton, N. J., assignor to Van
Vlaanderen Machine Co., Paterson, N. J., a
corporation of New Jersey

Original application September 11, 1942, Serial
No. 457,985. Divided and this application Jan-
uary 22, 1944, Serial No. 519,355

6 Claims. (Cl. 242—55)

This application is a division of my application
for patent for cloth measuring and tubing ma-
chine Serial No. 457,985, filed September 11, 1942.

The invention relates to machines for winding
fabric on successive cores, particularly in the
state for delivery to the selling trade, for which
purpose it is desired that, the lengths of the
fabrics in the different wound masses being the
same, all the masses shall be wound so as nearly
as possible to have the same density.

For this purpose the machine of this invention
contemplates presence therein, with a rotary
drum around which the fabric is to extend and
means to hold the fabric in contact with and
against slippage relatively to its periphery, and
with a rotary core on which to wind the fabric,
means by which to drive the core from the drum
through slip-friction which is capable of being
varied manually by the attendant. Thereby,
though as the wound fabric mass being formed
on the core tends to rotate at a constantly in-
creasing peripheral speed, with attendant in-
crease in tension on the fabric and increase in
density of the wound mass, the operator may
from time to time, by adjustment of the men-
tioned slip-friction core-driving means, com-
pensate for such tendency so as to attain tension
which during each operation will as nearly as
possible approximate constancy and a state of
density which in a succession of the wound
masses will be substantially uniform. In carry-
ing out my invention I have constructed the
machine specifically as follows: The drum has
its axis horizontal and the fabric, being delivered
from below the drum, extends over the drum and
then down under a freely rotative roll parallel
with the drum (and which affords in part the
means to hold the fabric in contact with and
against slippage relatively to the drum's peripher-
y) and then up to the core, which is also par-
allel with the drum; the drum, being suitably
driven, drives the core through a transmission
including a clutch comprising coaxial clutch-
members whose axis is also parallel with the
drum and one of which is driven by the drum
and the other of which drives the clutch; and
the manual adjustment of the clutch is effected
by a clamping means including a screw axially
related to the two clutch members and having
a manually operated nut. Thereby, the nut being
positioned in appropriate proximity to the drum,
the attendant can test the tension of the fabric
at any time by one hand and effect whatever
adjustment of the nut may be necessary by his
other hand.

The machine will usually be driven by a motor
having means to start and stop the same and
the fabric-supply will usually be a mass of the
fabric wound on a core or beam. This core, while
more or less free to turn (though preferably sub-

ject to friction resistance) during the winding,
should be checked instantly when the drum is
stopped by stopping the motor, else the fabric
would overrun. Hence, my invention further
5 contemplates control means so devised that,
when moved in one direction, it will stop the
motor and brake said core and, when moved in
the opposite direction, it will start the motor and
release the core.

10 In the drawings,
Fig. 1 is a front elevation of the improved ma-
chine, partly broken away;
Fig. 2 is a side elevation thereof with a part
of the near standard broken away;
15 Fig. 3 shows the winding means mainly in
longitudinal section;
Fig. 4 is a section on line 4—4 of Fig. 3;
Fig. 5 shows the electric circuit; and
Fig. 6 is an enlarged view of parts which in-
20 clude the clutch-member 41 appearing in Fig. 1
and viewed the same as in that figure.
The frame includes two standards 1 connected
by bars 2. What I term a carrier-rack is ar-
ranged to slide from one toward the other stand-
25 ard and comprises a rail 3 connecting a pair of
uprights 4 also connected by a bar 4a. This rail
has runners 3a which rest on rollers 1a jour-
naled in the standards, the left-hand one being
30 toothed to form a rack and the corresponding
roller existing as a pinion engaged with such rack
and having a hand-wheel 1b whereby manually
to shift the carrier-rack laterally so that the
selvages of the fabric may be lined up by the
35 operator with the ends of the wound mass being
formed. So much is the usual construction. The
carrier-rack is supported in upright position by
having the upper ends of its uprights engaged
40 with a shaft 21 to be referred to, said uprights
having open bearings 5 to receive the shaft 6 of
a beam or core 7 on which the supply-mass of
fabric a is wound.

In the left-hand standard is journaled the
axial portion 8 of a pair of peripherally grooved
drums 9 and 10, the rotary element thus formed
45 constituting a support for and having a socket
8a to receive the adjoining squared end of the
shaft 6, whereby such support forms a chuck—
confined to rotate with the beam 7. Fixed studs
50 11, one below and the other above said element,
project from the frame and to the lower one of
these a band or strap 12 is connected, the upper
terminal of the band penetrating the other stud
and being threaded and having a nut 13 for
55 tightening the band, which, between the studs,
bears against the periphery of the drum 9. Thus
a brake is formed which, on adjustment of the
nut, opposes some constant frictional resistance
to rotation of the beam and hence the delivery
60 of the fabric wound thereon. A pair of semi-
circular brake-shoes 14 pivoted to upper stud 11

engage the periphery of the drum 10. Pivot to the lower end of the rearward brake-shoe is a rearwardly projecting lever 15 and penetrating a boss 15a pivoted in the enlarged lower end of the other brake-shoe is a rod-like lever 16 whose other end is threaded and has a thumb-screw 17 to bear against the boss. The rear ends of the two levers are connected to a link 18, in turn connected with the plunger or actuated element 19 of a solenoid 20 or equivalent electrically energized means. In short, there is a twin-clutch the drum 9 of which (and hence the beam 7) is subject to constant resistance to rotation and the drum 10 of which is subject to resistance to rotation only on "call."

At a suitable elevation above and somewhat rearward of the beam 7 there is journaled in the frame the shaft 21 of a measuring drum 22. The fabric is to extend over and well around this drum, as back of it and then down and under an idle roll 23 forward of the drum and journaled in the frame, then back and forth around guide-bars 24 supported in suitable brackets 25 and then to the core b onto which the fabric is finally wound for delivery to the customer. In the upper part of the carrier-rack a pressure roll 22a (Fig. 2) is journaled and under the pressure of springs 22b holds the fabric pressed against the drum.

The core b is a pasteboard cylindrical tube one end of which is to be engaged with an idle chuck 26 journaled in a bracket 27 carried by the guide-bars. Its other end is to be engaged with an active chuck fully set forth in my application Serial No. 457,986 and which for the present purpose may be described as follows: A socket member 28 (here the driving member of the chuck) having a socket proper 28a has an axial spindle 29 received in the axial bore of and splined at 29a to a rotary tubular member here formed in two parts 30 and 30a journaled by ball-bearings 31 in a housing 32 carried by one of the standards 1, 33 being a spring between the left-hand end of the spindle and the closed end of the shaft-bore. Both the idle chuck and the element formed by parts 30-30a are of course confined by the supporting structure against displacement apart, as shown. (The housing 32 may be formed open at the top to admit a clock 50 to be referred to.) Free to turn in the socket on a stud coaxial therewith is a tapered plug member 35 (here the driven member of the chuck). The socket proper and plug member are both elliptical in cross-section and of such dimensions that each may rotate completely independently of the other except when the end of the core is introduced into the slot 36 between them in which case, if the socket member is turned while the plug member's rotation is resisted, as by the fabric, the lobes or humps 35a of the plug member will coact with what are in effect humps at 28a of the socket member to clamp the core end between them. The active chuck being at rest, the end of the core (tilted) is entered thereto and the core manipulated to displace the parts 28-29-34 against the tension of the spring until the other end of the core can be aligned with the idle chuck. When the socket member of the active chuck is now rotated the core will be now rotated by 70

A motor 37, supported by the left-hand standard, has its shaft 38 connected by a sprocket-and-chain drive 39 with the shaft 21 of drum 22. By gearing 40 shaft 21 drives a clutch member

41 journaled in the standard and having a clutch-disk 42 fast thereto. A sprocket-disk 43 is rotative on clutch member 41 and between the disks 42-43 and fast to one of them is a felt 5 or the like friction-disk 44. A shaft 45 penetrates the clutch member 41 axially, having a nut 46 formed with a hand-wheel 46a and screwed on its outer end and abutting said standard and a head (here in the form of a nut 47 on its inner end), and between such head and disk 43 is a spring 48; by turning the nut 46 the driven member (sprocket disk 43) of the clutch thus formed is gripped more or less tightly by the driving member 41 with its indicated means for clamping the driven clutch-member.

43a is a sprocket-chain engaged with the sprocket disk 43 on the driven clutch-member and also with a sprocket-wheel 49 on the part 30a of the active chuck for driving core b. 50 is a clock contained in housing 32 and geared in some way (not shown) with the measuring drum shaft 21.

On the forward bar 2 may be fulcrumed a treadle 51 whose forward end may be normally held elevated, as by a spring 52 (Fig. 1). When the treadle is depressed it closes the motor circuit 53 and opens the solenoid circuit 54 and when in its normal state it maintains the motor circuit open and the solenoid circuit closed; the treadle thus forms a circuit-closer.

Assume that the core b is held between the two chucks, with the upper end of the fabric wrapped around the core sufficiently tightly so that when rotation of the core is now started the wrapping will continue; to take up slack in the fabric the operator may turn the socket member by a hand-wheel 30b on part 30, it being assumed that in entering the core to the socket member its end is somewhat deformed and thus gripped thereby. The treadle is now depressed and the motor drives the measuring drum through the part of the transmission connecting them and the measuring drum drives the chuck and hence the core through that part 45 of the transmission which connects them. The depressing of the treadle leaves the delivery core 7 subject to the adjustable braking action of the means 9-12, whereby overrunning of such core is prevented, but such depression de-energizes the solenoid so that the braking effect of the members 14 becomes inactive. The winding of the fabric on core b therefore proceeds; during the winding slippage of clutch-member 43 occurs relatively to clutch-member 41, such being necessary since the fabric is kept advancing at constant speed by the measuring drum (against whose periphery it is firmly held against slippage by the means 22a and 23) whereas the mass being wound increases in diameter and so tends to increase the peripheral speed. By adjusting the pressure exerted on clutch-member 43 (to wit, by hand-wheel 46) the operator can determine the density of the wound mass being formed. When the winding is completed the treadle is allowed to rise, which cuts out the motor but energizes the solenoid, whereby the rotation of the fabric supply is checked. When the winding has been completed on any core b the fabric is cut to permit removal of the wound mass and substitution of an empty core.

The spring is present not only to permit ready entry of the core to and its removal from the two chucks but to maintain the distortion of the core end and hence displacement of a part or parts thereof within the range of a hump or

humps of the driving member of the active chuck in the case where, as here, the part of the driven member which is in telescoped relation to said core end is tapered lengthwise thereof.

Having thus fully described my invention, what I claim is:

1. In combination, supporting structure, a rotary drum journaled therein, means to hold the fabric being wound in contact with and against slippage relatively to the periphery of the drum, a chuck, journaled in said structure, to engage and rotate a core onto which to wind the fabric, and means, journaled in said structure, to transmit rotation from the drum to the chuck including rotary driving and driven clutch members in frictional contact with each other and manually adjustable means to urge one of said members under variable pressure against the other.

2. The combination set forth in claim 1 characterized by said members being coaxial.

3. In combination, supporting structure, a rotary drum journaled therein, means to hold the fabric being wound in contact with and against slippage relatively to the periphery of the drum, a chuck, journaled in said structure, to engage and rotate a core onto which to wind the fabric, and means, journaled in said structure, to transmit rotation from the drum to the chuck including coaxial driving and driven clutch members in frictional contact with each other and manually adjustable means, extending axially through said members, for clamping them together under variable pressure.

4. In combination, supporting structure, a rotary drum journaled therein, means to hold the fabric being wound in contact with and against slippage relatively to the periphery of the drum, a chuck, journaled in said structure, to engage and rotate a core onto which to wind the fabric,

and means to transmit rotation from the drum to the chuck including a rotary driving clutch member journaled in said structure, a driven clutch member coaxial and in frictional contact with the driving clutch member, and manually adjustable means, extending axially through the driving clutch member, for clamping said members together under variable pressure.

5. In combination, supporting structure, rotary means journaled therein and including a rotary core for a wound supply of sheet material, a rotary drum, also journaled in said structure, for exerting pulling effort on said material, means to hold said material in tractive engagement with the periphery of the drum, a motor for rotating the drum operatively connected therewith, braking means settable into braking or releasing relation to the first-named means, and means movable in one direction to start the motor and free the braking means and in the opposite direction to stop the motor and apply the braking means.

6. In combination, supporting structure, rotary means journaled therein and including a rotary core for a wound supply of sheet material, a rotary drum, also journaled in said structure, for exerting pulling effort on said material, means to hold said material in tractive engagement with the periphery of the drum, an electric motor having its driven element operatively connected with the drum to drive the same, electrically energized means to brake the first-named means, a branched circuit including the motor and last-named means in its respective branches, and a circuit-closer movable in one direction to close one branch and open the other and in the other to open the former branch and close the other branch.

GEORGE W. LANE.
